UNITED STATES PATENT OFFICE.

WILLIAM THORNBURGH, OF ELYRIA, OHIO.

GRINDSTONE-FRAME.

SPECIFICATION forming part of Letters Patent No. 373,254, dated November 15, 1887.

Application filed January 26, 1887. Serial No. 225,552. (No model.)

To all whom it may concern:

Be it known that I, WILLIAM THORNBURGH, of Elyria, in the county of Lorain, and the State of Ohio, have invented a new and Improved Grindstone-Frame, of which the following is a full, clear, and exact description.

The object of my invention is to provide a new and improved grindstone-frame which can be readily knocked down for transportation and easily and securely fastened together when it is to be used.

The invention consists in the construction and arrangement of various parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a side elevation of my improvement. Fig. 2 is a vertical cross-section of the same, on an enlarged scale, on the line $x-x$ of Fig. 1. Fig. 3 is a perspective view of the clamp, on an enlarged scale. Fig. 4 is a perspective view of the wedge, on an enlarged scale; and Fig. 5 is a perspective view of one end of a side bar.

The grindstone-frame A is provided with two sets of legs, B, which support the side bars, C. Each set of legs B is united with the side bars, C, by means of a clamp, D, a wedge, E, and a bolt, F. The clamp D, preferably of metal, is formed in the shape of a casing having open ends, and in its bottom a transverse slot, D², which is enlarged in the middle. A square aperture, D', is formed on the top of the clamp D, and through it passes the square part of the bolt F, which is thus prevented from turning.

The wedge E is preferably of metal, and is formed in the shape of a casing. This wedge fits into the middle portion of the slot D², and is provided with the inclined sides E' E', having flanges E². In the bottom of the wedge E is an aperture, E', through which passes snugly the lower threaded end of the bolt F, and the top of the wedge has a large opening, E⁴.

The side bars, C, carry bearings of any approved construction, in which the grindstone is journaled. Each outer end of each side

bar, C, is provided with an inclined recess, C', as shown in Fig. 5, and it corresponds to the angle at which the legs are set.

The grindstone-frame A is set up by slipping the side pieces, C, at each end into the corresponding clamp, D. Each set of legs B is then inserted into the respective clamp D, from underneath, into the transverse slot D², so that each leg rests with one inside edge in the recess C' of one side bar, C, as shown in Fig. 2. The wedge E is then placed between the legs B, with its inclined sides E' resting against the inner edges of the legs B, while the flanges E² prevent endwise motion of the wedge E. The bolt F is then inserted through the top aperture, D', of the clamp D, and passes through the openings E³ and E⁴ in the wedge E, and then the nut G is screwed on the threaded end of the bolt F and against the bottom of the wedge E, so that the latter is drawn upward and forces the legs B and the side bars, C, tightly in position in the clamp D, as shown in Fig. 2.

The grindstone-frame can be easily knocked down by unscrewing the nut G and removing the wedge E, after which the legs B and the side bars, C, can be easily removed from the clamps D.

Having thus fully described my invention, I claim as new and desire to secure by Letters Patent—

1. In a grindstone-frame, the combination, with the side bars and legs, of a clamp having openings in its bottom and sides, into which fit the ends of the said side bars and legs, a vertically-movable wedge fitting on the inside edges of the legs, and a bolt and nut for holding the wedge in place, substantially as shown and described.

2. In a grindstone-frame, the side bars, C, having a recess at each end, and the legs B, in combination with the clamps D, each having a transverse slot, D², and the aperture D', the wedge E, provided with the inclined sides E', the bolt F, and the nut G, for holding the several parts together, substantially as shown and described.

3. In a grindstone-frame, the side bars, C, having a recess near each end, and the legs B, in combination with the clamps D, each having a transverse slot, D², enlarged in the middle, and also the aperture D', the wedge E, pro-

vided with inclined sides E', having flanges E², the wedge being also provided with an apertured top and bottom, the bolt F, and the nut G, screwing on the said bolt and against the bottom of the said wedge, substantially as shown and described.

4. In a grindstone-frame, the clamp formed of a casting, D, having side openings, an angular aperture, D', in its top, and the longitudinal slot D² in its bottom, enlarged at its center, substantially as set forth.

5. In a grindstone-frame, the binding-wedge E, having apertures E¹ E³ in its top and base, respectively, and flanges E² at its opposite inclined edges, substantially as set forth.

6. A clamp and binding-wedge for grindstone-frames, comprising the casting D, having angular aperture D' in its top, side openings and centrally-enlarged slot D² in its bottom, and the wedge E, having apertures E¹ E³ in its top and bottom, and side flanges, E², and the bolt F, extending down through apertures D' E¹ E³ and having a nut, G, substantially as set forth.

WILLIAM THORNBURGH.
